UNITED STATES PATENT OFFICE.

LUCIUS E. COLEMAN, OF SANTA ANA, CALIFORNIA, ASSIGNOR TO
WILLIAM H. SPAKE, OF ANAHEIM, CALIFORNIA.

ADDING DEVICE.

No. 816,781.

Specification of Letters Patent

Patented April 3, 1906.

Application filed January 21, 1903. Renewed February 10, 1906. Serial No. 300,496.

To all whom it may concern:

Be it known that I, LUCIUS E. COLEMAN, a citizen of the United States, residing at Santa Ana, in the county of Orange and State of California, have invented a new and useful Adding Device, of which the following is a specification.

This invention relates to an improved adding device, and more particularly to a disk 10 for registering the tens in adding a column of figures, and has for its object to provide a simple, inexpensive, and efficient device of this character adapted to assist a person in the process of addition and by means of which 15 one or more columns of figures may be quickly and accurately added without unnecessarily burdening or taxing the memory with a multiplicity of figures.

A further object of the device is to provide 20 a registering-disk for registering the tens in a column of figures in the process of addition, the right-hand digit being kept in the mind and varied according to the change necessitated by the addition of a figure or group of 25 figures in adding the column.

The invention consists in a disk having 30 stamped, embossed, or otherwise imprinted on its face an annular row or series of numerals representing tens in consecutive order 35 from one to twenty-six or more, the periphery of the disk being provided with notches or depressions corresponding to the numbers representing the tens inscribed on its face, the disk being adapted to be held in the hand 40 and rotated, the forefinger engaging the particular notch or depression in the periphery of the disk corresponding to the tens in a column of figures as they appear in adding.

The invention further consists in the construction and novel combination and arrangement of parts hereinafter fully described, illustrated in the accompanying drawings, and pointed out in the claims hereto appended.

In the drawings, Figure 1 is a perspective 45 view showing the manner of operating the regulating-disk. Fig. 2 is a rear view of the same.

Similar numerals of reference indicate corresponding parts in both figures of the drawings.

1 designates the register, which consists of a flat disk 2, circular in contour and formed of sheet metal or other suitable material, being preferably die-struck and formed with

55 peripheral notches or depressions 3, defining a series of radiating points or spurs 4. On the face of the disk 2 and preferably near its periphery are stamped, embossed, or otherwise imprinted an annular row or series of numerals representing in consecutive order 60 tens from one to twenty-six or more, and these numerals are preferably arranged on the face of the disk, so that one number will appear directly under each of the radiating points or spurs 4. On the rear side or face 65 of the disk 1 are inscribed a similarly-arranged annular row of numerals, the notches or depressions in the periphery of the disk coacting in like manner to register the tens, or, if desired, the numerals instead of being 70 arranged directly under the spurs may be arranged below the notches or depressions, as clearly shown in Fig. 2 of the drawings. The spurs 4 are preferably slightly rounded, as shown, to prevent pricking or otherwise 75 lacerating the fingers while operating the register.

In practice the disk is held in the left hand with the forefinger resting in the notch or depression represented by the higher numeral "26" in the present instance, as clearly shown in Fig. 1 of the drawings, and in adding a column of figures the tens are registered on the disk by moving the finger from one notch to the next as they appear in the process of adding, the units only being carried from one figure or group of figures to the next. For instance, if it is desired to add "89," "97," "68," and "46" one would proceed as follows for the first column: Six and 80 eight are fourteen; the ten is registered on the disk by moving the finger in the first notch and the four units carried. Four and seven are eleven; move the finger to the second notch and carry the one. One and nine are 85 ten; move the finger to the third notch and put down "0." Now by looking at the register we find we have registered three tens, so we have three to carry to the next column, and so on. Any number of columns of any 90 length may be added in like manner, not more than eighteen units being carried in the mind at one time.

From the foregoing description it will be seen that I have provided an exceedingly 105 simple, inexpensive registering-disk by means of which the adding of one or more columns of figures is greatly facilitated, which may be

used for instructing children in arithmetical problems, as well as by auditors in general, and being of approximately the size and shape of a coin may be carried as a pocket-piece.

5 While I have only shown the numerals representing the tens running from one to twenty-six, it is obvious that the disk may be provided with as many numbers as desired, and various changes in form, proportion, and 10 minor details of construction may be resorted to without departing from the principle or sacrificing any of the advantages of the invention.

Having thus described the invention, what 15 I claim is—

A device for keeping account of the tens in the process of addition comprising a light portable disk adapted to be held in the hand

and revolved one step whenever ten units have been added, said disk having peripheral notches and spurs, such spurs being of sufficient height to indicate by their passages over the thumb and finger that the disk has been moved one notch, said disk bearing on its opposite faces marginal rows of numerals, 25 each numeral being disposed adjacent to one of the notches or depressions for the purpose specified.

In testimony that I claim the foregoing as my own I have hereto affixed my signature 30 in the presence of two witnesses.

LUCIUS E. COLEMAN.
